UNITED STATES PATENT OFFICE.

THOMAS HUMMEL, JR., OF PEORIA, ILLINOIS.

DESIGN FOR AN EASEL.

SPECIFICATION forming part of Design No. 21,665, dated June 28, 1892.

Application filed May 19, 1892. Serial No. 433,634. Term of patent 3½ years.

To all whom it may concern:

Be it known that I, THOMAS HUMMEL, Jr., a citizen of the United States, residing at Peoria, in the county of Peoria and State of Illinois, have invented and produced a new and original Design for Easels, of which the following is a specification, reference being had to the accompanying drawings, showing a part thereof.

10 Figure 1 is a front elevation of an easel constructed and formed according to my design. Fig. 2 is a side elevation, or rather an edge view, of the same.

The leading features of my design consist 15 in a horseshoe-shaped middle portion mounted upon gnarled wooden legs, a deer's head and musket forming the lower connection between the legs of the easel, a shield, and an eagle, substantially as shown.

20 In the figures the horseshoe is shown with the heel portion downward and provided upon its face with the usual grooves and perforations provided for the nails and with toe and heel calks, which in this connection may pro-

25 vide a bearing for a picture designed to be carried upon the easel; but generally a picture is designed to be placed at the back of the horseshoe, the shoe thus forming a frame. The forward legs of the easel are shown of

gnarled wood and connected with the lower 30 ends of the horseshoe, and between the said forward legs is suspended a deer's head provided with antlers, two of which connect with the legs at their juncture with the lower portion of the horseshoe, the said deer's head 35 continuing backward to form a bust mounted upon a suitable bracket and connecting forward legs at their middle portion, and bearing across immediately below the deer's head is a musket properly formed and attached. 40 Upon the top of the shoe or its toe portion is mounted edgewise a shield formed as shown and with the face thereof provided with an open field at its upper portion or end portion as here adjusted and with its lower portion 45 proper divided into bars or stripes, and surmounting the shield is an eagle grasping a spear in its talons.

Having thus fully described my invention, what I claim, and desire to secure by Letters 50 Patent, is—

The design for an easel, as herein shown and described.

THOMAS HUMMEL, JR.
